UNITED STATES PATENT OFFICE

WALTER A. O'BANNON, OF TULSA, OKLAHOMA, ASSIGNOR TO WALTER O'BANNON CO.,
A CORPORATION OF OKLAHOMA

SLIP SOCKET

Original application filed March 6, 1929, Serial No. 259,544. Divided and this application filed May 23, 1929. Serial No. 365,395.

Known fishing tools of the sucker rod type commonly embody one or more slip units, each composed of complementary sections which are held in their cooperative relation, if at all, by some element which merely acts to prevent displacement of one section relative to another axially of their support while permitting of their expansion or opening action only incident to movement of the sucker rod passing into the unit.

I have found it advantageous to maintain the slip unit in expanded condition against the walls of the socket barrel, as this insures at all times the maximum opening of the slips and proper engagement with the sucker rod or its joint. One of the main objects of the present invention is to provide a slip construction embodying novel resilient means which not only serves to maintain the slip sections properly disposed or aligned, but also tends to expand said sections and cause them to follow the wall of the barrel, in which they are seated, as the slips move upwardly, this application constituting a division of my copending application filed March 6, 1929, Serial No. 259,544.

Referring to the drawings:

Fig. 1 is a longitudinal sectional view of an embodiment of this invention; and
Fig. 2 is a detail view of the expander member used in connection with the slip unit.

The invention which forms the subject matter of this application comprises the usual barrel or bowl 1 which is internally threaded at its upper end to receive the connector head 2, having a threaded extension by means of which the head may be screwed into the barrel. At its lower end the bore of the barrel is tapered and within this tapered portion is seated a slip unit 3 which is tapered externally to conform to the shape of the barrel taper. The slip unit is composed of a plurality of sections to enable it to expand and contract in performing the gripping function incident to the fishing of a sucker rod from a well. To enable it to grip the rod, the bore of the slip unit is provided with the customary wickers, and while the bore shown in the drawing is formed with parallel walls, it is to be understood that

said bore may be formed with a taper, as conventional in this art, so as to enable it to take different sized rods or to catch a rod which may be broken adjacent to the joint or box.

At the top of the bore the slip unit is formed with an internal groove to receive an expander member or spring ring 4, shown clearly in Fig. 2 of the drawings. This ring by virtue of being seated in the groove is naturally interlocked with the slip unit against displacement by an object which may pass into and through the bore of the slip unit. The object of this spring is two-fold: In the first place, it is designed to prevent longitudinal displacement of one of the slip sections relative to the other, and, in the second place, the ring by virtue of its expansion characteristics tends to cause the slip sections to follow the wall of the barrel or bowl when it is moved upwardly in the latter during the fishing operation. As shown in Fig. 2, the ring is made of flat steel and the ends thereof overlap sufficiently to insure a closed ring when the slip sections are expanded to the fullest extent.

In the use of this sucker rod socket, it is lowered into the well casing until it contacts with the "catch" or the sucker rod. The rod is caused to pass into the barrel, into contact with the slip unit 3 which moves upwardly and expands during such upward movement. When the movement has stopped, during which the rod passes into the bore of the slip unit, the barrel or socket body is elevated, thereby causing the relative movement downwardly of the slip unit, which upon reaching the tapered bore closes on the sucker rod until the teeth or wickers bite into the metal. In this manner the continued upward movement will result in the pulling of the sucker rod.

Having thus described my invention, which I claim as new and desire to secure by Letters Patent of the United States is:—

1. A sucker rod socket comprising a barrel, a slip unit mounted therein and composed of complementary gripping sections, and separate means common to and interlocking with said sections and tending to ex-

5 expand the sections into contact with the barrel walls with movement of the slip unit upwardly within the barrel and preventing longitudinal displacement of the sections relative to each other.

10 2. A sucker rod socket comprising a barrel, a slip unit mounted therein and composed of complemental gripping sections, separate means common to said sections and tending to expand the sections into contact with the barrel walls in the movement of the slip unit upwardly within the barrel and preventing longitudinal displacement of the sections relative to each other, and means for 15 preventing displacement from said unit of the expanding means aforesaid during the use of the device.

20 3. A sucker rod socket comprising a barrel, a slip unit mounted therein and composed of complemental sections, said unit having an inner annular groove extending continuously from one section to another, and an expander member mounted in said groove permitting free opening and closing 25 movements of the sections.

30 4. A sucker rod socket comprising a barrel, a slip unit mounted therein and composed of complemental sections, and a split expansion ring seated within the bore of 35 the unit and having its ends slidingly overlapping.

40 5. A sucker rod socket comprising a barrel, a slip unit mounted therein and composed of complemental sections, said slip unit being provided with a wickered bore and an internal groove intermediate the length of said bore, an expander spring seated within said groove tending to expand 45 said slip sections in the movement of the slip unit upwardly within the barrel, and a spring coacting with said slip unit tending to hold the slip unit at the lower end of the barrel.

In testimony whereof I affix my signature.
45 WALTER A. O'BANNON.
